(57) **CLAIM**

The design for an industrial robot, as shown and described.

DESCRIPTION

FIG. 1 is a front view of an industrial robot of a new design; FIG. 2 is a back view of the industrial robot shown in FIG. 1; FIG. 3 is a left side view of the industrial robot shown in FIG. 1;

FIG. 4 is a right side view of the industrial robot shown in FIG. 1;

FIG. 5 is a top view of the industrial robot shown in FIG. 1; FIG. 6 is a bottom view of the industrial robot shown in FIG. 1;

FIG. 7 is a front perspective view of the industrial robot shown in FIG. 1;

FIG. 8 is a front view of a second embodiment of the industrial robot;

FIG. 9 is a back view of the industrial robot shown in FIG. 8; FIG. 10 is a left side view of the industrial robot shown in FIG. 8;

FIG. 11 is a right side view of the industrial robot shown in FIG. 8;

FIG. 12 is a top view of the industrial robot shown in FIG. 8; FIG. 13 is a bottom view of the industrial robot shown in FIG. 8; and,

FIG. 14 is a front perspective view of the industrial robot shown in FIG. 8.

The article of the present designs relate to an industrial robot having multi-joints capable of performing various processing operations.

The broken lines in the drawings depict unclaimed environmental subject matter.
